UNITED STATES PATENT OFFICE.

DANIEL FRANCIS DALTON, OF WATERBURY, CONNECTICUT, ASSIGNOR TO THE SHOE HARDWARE COMPANY, OF WATERBURY, CONNECTICUT, A CORPORATION OF CONNECTICUT.

STRAP BUCKLE.

Application filed July 6, 1923. Serial No. 649,791.

To all whom it may concern:

Be it known that I, DANIEL FRANCIS DALTON, a citizen of the United States, residing at Waterbury, county of New Haven, State 5 of Connecticut, have invented certain new and useful Improvements in Strap Buckles, of which the following is a full, clear, and exact description.

This invention relates more particularly 10 to buckles having a sliding plate which contacts with a fixed frame to grip and securely hold the strap in fixed position.

The principal object of the present invention is to improve this type of buckle by 15 rendering it more durable and attractive while maintaining its simplicity of construction.

Referring to the drawings forming part 20 of this specification;

Fig. 1 is a plan view of the buckle inverted;

Fig. 2 is a sectional view through the line 2-2 of Fig. 1;

Fig. 3 is a plan view of a modified form 25 of buckle inverted;

Fig. 4 is a sectional view through the line 4-4 of Fig. 3;

Fig. 5 is a plan view of another modification 30 of the buckle inverted;

Fig. 6 is a sectional view through the line 6-6 of Fig. 5; and

Fig. 7 is a sectional view of the buckle shown in connection with the strap or belt.

The buckle comprises a fixed member or 35 frame A and a clutch slide-plate B. The frame comprises two side bars 1-1 and transverse bars 2-3. A third transverse bar 4 is also shown which may be employed if desired, the three bars being connected to 40 the side bars 1-1, thereby forming front and rear slots 5 and 6 respectively for the reception of the strap C (see Fig. 7). Flanges 7-7 are formed on the outer edges of the side bars and turned over to form 45 oppositely disposed guide-ways 8-8.

The clutch slide-plate comprises two side bars 9-9 slidably engaged by the guide-ways 8-8, and in the form here shown the ways are constructed of sufficient length to 50 retain the sides of the plate entirely throughout their lengths in any position of the plate relative to the frame. Two transverse bars 10 and 11 are connected to the side bars 9 of the plate to form a slot 12 for the reception 55 of the strap which is disposed to reg-

ister with the slot 5 in the frame when the plate is in retracted position to form an open slot entirely through the buckle of sufficient width to receive the strap.

A flange 13 is formed on the front of the 60 plate B and is folded tightly over upon the plate to form a rounded front edge 14 and a reinforced front wall of double thickness, the folded flange is turned up to form a lip 15 projecting from the front of the slot 12. As is obvious both the frame A and slide-plate B may be stamped from sheet 65 metal and suitably folded to form the parts above described. The buckle is manipulated in securing and releasing the strap C in a 70 similar manner to the buckle shown in the patent to Kerngood No. 1,049,732, which operation is common to all buckles of this type and therefore no further description 75 thereof is considered necessary here.

While in Figs. 3 and 4 the transverse bar 4 is used for securing the buckle to the garment, in the form of buckle shown in Figs. 1, 2, 5, 6, and 7 a transverse bar 16 is provided for attaching the buckle to the garment. This bar is raised from the frame as clearly shown in Fig. 2 and has its ends somewhat enlarged and bent to form right angles, the free legs or ends 17 being formed with openings 18. These ends 17 are held 80 firmly in the ways 8 by bending or setting the metal of the flanges into the openings 18 as shown at 19 Fig. 2. The plate B is arrested in its forward and rearward movements in the forms of buckles here shown 85 by co-acting means forming part of the plate and part of the frame respectively. For this purpose, in the form of buckle shown in Fig. 1 the attaching bar 16 is considered part of the frame and is suitably positioned to form a stop for the plate B so that when it reaches its rearward position the rear end of the plate will strike the ends of the bar within the ways 8 which will take 90 place when the slots 5 and 12 are in registering positions as already described. To stop the plate at its extreme forward position the lip 15 is provided with end extensions 20 projecting laterally beyond the folded flange, and the forward ends of the flanges 7 are provided with lugs 21 projecting toward each other in the path of the respective ends 20 to co-act therewith to stop 95 the plate at said forward position. In Figs. 3 to 6 inclusive a different construction is 100

105

110

shown for stopping the plate in its forward and rearward movements. In this form of buckle the side flanges 7-7 are cut to form oppositely disposed slots 22 and the plate is provided with oppositely disposed lugs 23 which are engaged by the slots 22. The lugs 23 will strike the end walls of the slots as the plate is moved back and forth and the slots are made of suitable length so that the lugs 23 will strike the end walls of the slot as the plate reaches its extreme forward and rearward movements. The style of buckle shown in Figs. 5 and 6 is a combination of the buckles shown in the other views. In this form of buckle the attaching bar 16 of Figs. 1 and 2 is employed, and the stopping means comprising the slots 22 and lugs 23 of Figs. 3 and 4 is employed.

When the buckle of the several forms here shown is in position for use, that is to say right side up, as shown in Fig. 7, the stopping means for the plate B is concealed from view, entirely so in Figs. 1 and 2 and substantially so in the other form of buckle shown in the other views thereby presenting a very neat and attractive appearance. Moreover the rounding edge 14 of the folded front portion of the plate provides a smooth surface admirably adapted to serve as a finger piece when it is desired to force the plate back, and for this purpose the rounded folded end may project as far as desired beyond the frame in its forward position. The folded-over front portion of the plate gives additional strength and rigidity and adds to the durability of the buckle.

Having thus described my invention what I claim and desire to protect by Letters Patent is:—

1. In a strap buckle, a frame comprising two side bars, three transverse bars connected to the side bars to form front and rear slots for the reception of the strap, flanges formed on the outer edges of the side bars turned over to form oppositely disposed guide-ways, a clutch slide-plate comprising two side bars slidably engaged by the ways, the ways being of sufficient length to retain the sides of the plate throughout their entire lengths in any position of the plate relative to the frame, two transverse bars connected to the side bars of the plate to form a slot for the reception of the strap disposed to register with the front slot in the frame when in retracted position, a flange extending from the front edge of the plate folded upon the plate to form a rounded front edge and a reinforced front wall of double thickness, a lip projecting from the edge of the folded flange at the front of the slot formed in the plate, and means forming part of the plate and frame respectively adapted to co-act to arrest the forward and rearward movements of the plate.

2. In a strap buckle, a frame comprising two side bars, transverse bars connected to the side bars to form a slot for the reception of the strap, flanges formed on the outer edges of the side bars turned over to form oppositely disposed guide-ways, a clutch slide-plate comprising two side bars slidably engaged by the ways, two transverse bars connected to the side bars to form a slot for the reception of the strap disposed to register with the slot in the frame when in retracted position, a lip projecting from the plate at the front of the slot formed therein, and lugs projecting toward each other from the forward end of the flanges in the path of the respective ends of the lip to co-act therewith to stop the plate at its extreme forward position.

3. In a strap buckle, a frame comprising two side bars, transverse bars connected to the side bars to form a slot for the reception of the strap, flanges formed on the outer edges of the side bars turned over to form oppositely disposed guideways, a clutch slide-plate comprising two side bars slidably engaged by the ways, two transverse bars connected to the side bars to form a slot for the reception of the strap disposed to register with the slot in the frame when in retracted position, a flange extending from the front edge of the plate folded upon the plate to form a rounding front edge and a reinforced front wall of double thickness, a lip projecting from the edge of the folded flange at the front of the slot formed in the plate, and lugs projecting toward each other from the forward end of the side flanges in the path of the respective ends of the lip to co-act therewith to stop the plate at its extreme forward position.

4. In a strap buckle, a frame comprising two side bars, transverse bars connected to the side bars to form a slot for the reception of the strap, flanges formed on the outer edges of the side bars turned over to form oppositely disposed guideways, a bar for attaching the buckle having its ends secured in the respective guide-ways, a clutch slide-plate comprising two side bars slidably engaged by the ways and adapted to strike the said secured bar to arrest its rearward movement, a lip projecting from the plate at the front of the slot formed therein, and co-acting means formed on the plate and frame respectively for arresting the forward movement of the plate.

5. In a strap buckle, a frame comprising two side bars, transverse bars connected to the side bars to form a slot for the reception of the strap, flanges formed on the outer edges of the side bars turned over to form oppositely disposed guide-ways, a bar for attaching the buckle having its ends secured in the respective guide-ways, a clutch slide-plate comprising two side bars slid-

ably engaged by the ways and adapted to strike the said secured bar to arrest its rearward movement, a flange extending from the front edge of the plate folded upon 5 the plate to form a rounding front edge and a reinforced wall of double thickness, a lip projecting from the edge of the flange at the front of the slot formed in the plate and having its ends extending laterally beyond the folded flange, and lugs project-

ing toward each other from the forward end of the side flanges in the path of the respective extending ends of the lip to coact therewith to stop the plate at its extreme forward movement.

15

Signed at Waterbury, county of New Haven and State of Connecticut, this 29th day of June, 1923.

DANIEL FRANCIS DALTON.
